US00D707192S

(12) **United States Design Patent**
Hussell et al.

(10) **Patent No.:** **US D707,192 S**
(45) **Date of Patent:** **** Jun. 17, 2014**

(54) **LIGHT EMITTING DEVICE**

(75) Inventors: **Christopher P. Hussell**, Cary, NC (US);
Erin R. F. Welch, Chapel Hill, NC (US);
Peter Scott Andrews, Durham, NC (US); **Jesse Colin Reiherzer**, Wake Forest, NC (US); **David T. Emerson**, Hillsborough, NC (US)

(73) Assignee: **Cree, Inc.**, Durham, NC (US)

(**) Term: **14 Years**

(21) Appl. No.: **29/412,168**

(22) Filed: **Jan. 31, 2012**

Related U.S. Application Data

(60) Continuation-in-part of application No. 29/407,084, filed on Nov. 22, 2011, now Pat. No. Des. 667,803, and a continuation-in-part of application No. 29/408,995, filed on Dec. 19, 2011, now abandoned, and a continuation-in-part of application No. 29/380,387, filed on Dec. 3, 2010, now Pat. No. Des. 676,000, said application No. 29/407,084 is a division of application No. 29/379,363, filed on Nov. 18, 2010, now Pat. No. Des. 649,061, said application No. 29/380,387 is a continuation-in-part of application No. 29/379,363, filed on Nov. 18, 2010, now Pat. No. Des. 649,061.

(57) **CLAIM**

The ornamental design for a light emitting device, as shown and described.

DESCRIPTION

FIG. 1 is a perspective view of a light emitting device showing our design;

FIG. 2 is a top view thereof;

FIG. 3 a side view thereof, the opposing and adjacent sides being mirror images of that shown; and,

FIG. 4 is a bottom view thereof.

The dashed broken lines are for illustrative purpose only and form no part of the claimed design. The dot-dash broken lines represent boundaries of the claimed design and form no part of the claimed design.

1 Claim, 3 Drawing Sheets
